UNITED STATES PATENT OFFICE.

OTTO C. BRITSCH, OF MASPETH, NEW YORK, ASSIGNOR TO DAVID WALL,
OF NEW YORK, N. Y.

MECHANISM FOR OPERATING ELECTRIC MOTORS AND CONTROLLING THE SPEED OF DEVICES ACTUATED THEREBY.

SPECIFICATION forming part of Letters Patent No. 782,593, dated February 14, 1905.

Application filed May 16, 1904. Serial No. 208,107.

To all whom it may concern:

Be it known that I, OTTO C. BRITSCH, a citizen of the United States, residing at Maspeth, county of Queens, State of New York, have 5 invented an Improvement in Mechanism for Operating Electric Motors and Controlling the Speed of Devices Actuated Thereby, of which the following is a specification.

My invention relates to mechanism for operating electric motors and controlling the speed of devices actuated thereby, and in carrying out the same I employ in combination with a motor and a suitable support therefor a rocking lever pivotally connected to the 15 motor-frame and adapted to be actuated by the foot of the operator through the means of a suitable treadle or otherwise, means actuated upon the rocking movement of the said lever for closing the electric circuit to the 20 motor, means also actuated by the rocking movement of said lever and according to the extent of said movement to regulate the speed of devices driven by the motor, and means upon the release of the treadle by the operator 25 for returning said parts to or toward an initial position for breaking the circuit to the motor and stopping the devices driven by the motor independently of the motor-shaft.

In the drawings, Figure 1 is a side elevation 30 of the devices comprising my present invention; and Fig. 2 is a plan view of the same, taken at right angles thereto. Fig. 3 is a front elevation showing the parts with the regulating-lever removed, and Fig. 4 is a similar view with the rocking lever in position. Figs. 5, 6, and 7, are respectively an end elevation and opposite side elevations of the pulley, and Fig. 8 is a cross-section on the dotted line w-w of Fig. 6. Fig. 9 represents a section 35 40 of a modified form of clutch, and Figs. 10 and 11 are diagrammatic views of the electric circuits.

a represents a motor-frame which is provided with suitable brackets a' , by means of 45 which the motor-frame is secured to its support.

a^2 a^3 represent the journals for the motor armature-shaft, and a^3 represents a suitable cap through which circuit-wires are brought to the motor.

At one side the motor-frame is provided with a casing 1 , and I employ a rocking lever b , mounted pivotally on a pin b' , secured in the casing 1 . The free end of the rocking lever b is provided with an opening by means of 50 which the same is connected to a treadle or other device adapted to be operated by foot-power through a connecting-rod c . The casing 1 is also provided with a lug 2 , in which one end of a spring c' is secured, the opposite end of the spring c' being fixed in a bracket f on the inner side of the free end of the rocking lever b . The function of the said spring is to raise this end of the rocking lever. The opposite end of the rocking lever b is 55 provided with a bracket d , having a downward projection d' , at the end of which is secured, by means of screws 4 , a wedge-plate. The upper surface of the bracket d is provided with set-screws 3 , the function of which 60 will be hereinafter described. A screw passes vertically through the lug 2 directly beneath the free end of the lever b and which in its lowered position contacts with this end of the screw, so that in one direction the extent of the movement of the lever is limited 65 according to the position in which the screw c' is set, and the wedge-plate c is laterally adjustable by means of a screw d'' .

As hereinbefore stated, the free end of the 70 rocking lever b is provided on the inner side with the bracket f , and the casing 1 is provided with a plate f' , by means of which a suitable shield (not shown) adapted to cover the parts may be connected to the casing.

h represents an arm pivoted at 5 at one end thereof in the casing 1 , and at the opposite end provided with a carbon or other terminal i , secured therein by means of a screw 7 or otherwise, and the pivotal point 5 is electrically connected to the terminal i . I employ 85 a block g , preferably of insulating material

and cylindrical and passing through a hub f^2 , depending from the plate f' . The lower end is adapted to bear on the face of the bracket f , and the upper end to pass through the plate f' , and to contact with the under side of the arm h at the point adjacent to its fulcrum and supports the arm h in the position shown in Figs. 3 and 4. The casing 1 is also provided with a small plate 6, and by this plate and a spring h' the arm h is normally held against the upper reduced end of the block g . Directly beneath the contact i I employ a carbon or other contact i' , secured in a suitable terminal 8 by a screw 9 or otherwise.

15. k represents a pulley provided centrally with a circumferential semicircular groove k' . This pulley k is preferably cast hollow and the hub l' thereof is lined with suitable bushings 10 and 11. At one side of the pulley k 20 a flat split spring l is secured by a suitable block 12 and screw 13. The ends of the spring l are preferably inturned and terminate at a point diametrically opposite the block 12, the hub l' being preferably flattened at opposite sides, and against one of these flattened sides one edge of the block 12 contacts. At the opposite side the pulley k is provided with a recess 14, adapted to be covered by a suitable plate 15. The plate 15 is provided centrally 25 with an opening through which passes a button m . The button m is provided with a transverse recess and an inclined surface 16, leading therefrom to the outer portion of the button, and the end of the button is recessed to receive a small steel ball m' . In connection with the pulley I employ a rod n , passing longitudinally through the same and provided at one end with a finger n' , which passes through the recess 14 and into the transverse 30 recess in the side of the button m and is normally held in position within the bottom of said recess by means of a spring o . The opposite end n^2 of the rod n is flattened and is received between the inturned ends of the spring l . The pulley k may be packed with wick 17 or other suitable material adapted to be saturated with oil for lubricating purposes, and at one side the said pulley is also provided with an opening 18 and oil-button 35 19, a spring 20, and a screw-plug 21, the spring 20 maintaining the button 19 in position in its socket.

50. The motor-armature shaft is provided with a cup-shaped sleeve o' , and the said shaft is adapted to receive the pulley k with its attachments, in such position that the spring l fits within the cup-shaped sleeve o' and the wedge-plate e in contact with the ball m' . The bracket d is provided with a brake-block g' , situated when the pulley is in position immediately above the circumferential groove k' therein. This brake-block g' is secured in position within the bracket d by means of

screws 3 and may be adjusted to any desired height within its limits by means of adjusting-screws g^2 , passing through the top of the bracket.

Normally the parts are in the position indicated in the drawings, and now it is believed that it will be readily apparent that by depressing the treadle and lowering the free end of the rocking lever b , through the connecting-rod c , that the block g and arm h will drop by gravity, the arm h being lowered sufficiently to allow the carbon i in its free end to come in contact with the carbon i' , secured in the terminal 8, thereby completing the circuit to the motor. The lowering of the free end of the lever b raises the opposite end thereof and causes the wedge-plate e to force the button m inward. This action causes the finger n' to ride upon the inclined face 16 against the action of the spring o , thereby imparting a turning movement to the rod n , causing its flattened end n^2 to force the parts of the spring l apart, in which position said parts of the spring l engage the inner surface of the cup-shaped sleeve o' and bind the pulley to the said cup-shaped sleeve and through the same to the armature-shaft. The rope or belt employed to drive the devices actuated by the motor passes around the pulley in the circumferential groove, and it is believed that it will also be apparent that the speed imparted thereto will be dependent upon the distance the treadle has raised the downward projection d' , connected to the rocking lever b . The greater the downward movement of the treadle the greater the lift of the projection d' and plate e , and consequently the tighter the grip brought to bear between the surfaces or parts of the spring l and the inner surface of the cup-shaped sleeve o' .

In Fig. 9, 22 represents the motor-armature shaft, to which is secured a flange 23 by means of a screw 24. The flange 23 is provided with a circular groove, in which is set a washer 25, of leather or other suitable material. In this modification of the invention the pulley is represented at 26, and one face thereof is adapted to contact with the surface of the washer 25, against which it is held by means of the wedge-plate e , through a ball m^2 , corresponding to the ball m' in the other figures.

In order to bring the motor up to speed properly, I may employ a rocking lever h^2 , pivotally connected to the free end of the arm h , as shown diagrammatically in Figs. 10 and 11, in which 28 represents the motor, a series motor being shown in Fig. 10 and a shunt-wound motor being shown in Fig. 11. When the lever h^2 is employed, one end thereof is preferably provided with a contact 29 and the opposite end with the contact 30, and the terminal 31 is connected to a terminal 33 by means of a resistance-coil 32, which resistance-

coil is preferably provided with an iron core 34. In the operation of this apparatus the contact 30 first closes the circuit through the terminal 31 and the resistance-coil 32, and when the arm *h* is lowered sufficiently the motor-circuit is completed directly through the contact 29 and terminal 33, the iron core 34 being employed as an arc-extinguisher, it being well known in the art that an electrical arc cannot exist in a magnetic field.

I claim as my invention—

1. The combination with an electric motor and its armature-shaft, of an oscillating arm and coacting parts performing the functions of a switch to make and break the electric circuit to said motor, a lever pivoted in the motor-frame and adapted to be operated by foot-power and actuating said arm, a clutch on the armature-shaft and means actuated by the movement of the said lever for engaging and disengaging said clutch.

2. The combination with an electric motor and its armature-shaft, of a lever pivoted in said motor-frame and adapted to be actuated by foot-power, a clutch on said shaft, means in connection with said lever and adapted to normally exert a pressure against the free member of said clutch, means for normally maintaining the lever in position with the aforesaid means performing its function, means actuated by the movement of said lever to engage and disengage the said clutch, and means controlled by a movement of said lever to make and break the electric circuit to the motor.

3. The combination with an electric motor and its armature-shaft, of a lever pivoted in the motor-frame and adapted to be actuated by foot-power, electrical terminals, an arm pivoted on one of said terminals, a contact carried by said arm and adapted to engage the other terminal, means for connecting said arm with said lever and means actuated by the movement of said lever for connecting and disconnecting the said shaft with the devices driven by the motor.

4. The combination with an electric motor and its armature-shaft, of a lever pivoted in the motor-frame and adapted to be actuated by foot-power, electrical terminals, an arm pivoted on one of said terminals, a contact carried by said arm and adapted to engage the other terminal, a bracket integral with said lever, a block extending between said brake and said arm, means for maintaining said arm in a normal position with the said contact away from the said terminal, and means actuated by the movement of said lever for connecting and disconnecting the said shaft with the devices driven by the motor.

5. The combination with an electric motor and its armature-shaft, of a lever pivoted in said motor-frame and adapted to be actuated

by foot-power, a bracket integral with said lever, electrical terminals, an arm pivoted at 65 one of said terminals, a contact carried by said arm and adapted to be electrically connected to the other terminal, a block extending between said bracket and said arm, a spring for normally maintaining said bracket 70 and arm in such position that the said contact and terminal are electrically disconnected, a spring for maintaining the said arm in position against the said block, and means actuated by the movement of said lever for connecting and disconnecting the said shaft with the devices driven by the motor.

6. The combination with an electric motor and its armature-shaft, of a lever pivoted in said motor-frame and adapted to be actuated 80 by foot-power, a pulley loose on said shaft, a cup-shaped sleeve fixed on said shaft, means in connection with said pulley for frictionally engaging the said cup-shaped sleeve, means actuated by a movement of said lever for actuating the aforesaid means, and means controlled by a movement of the said lever for making and breaking the electric circuit to the motor.

7. The combination with an electric motor 90 and its armature-shaft, of a lever pivoted in the motor-frame and adapted to be actuated by foot-power, a pulley loose on said shaft, a cup-shaped sleeve fixed on said shaft, a split spring fixed on said pulley, means actuated 95 by the movement of said lever for spreading the parts of said spring causing the same to engage the said cup-shaped sleeve, and means controlled by a movement of said lever in making and breaking the electric circuit to the motor.

8. The combination with an electric motor and its armature-shaft, of a lever pivoted in said motor-frame and adapted to be actuated by foot-power, a pulley loose on said shaft, a cup-shaped sleeve fixed on said shaft, a divided 105 spring secured in one side of said pulley, a rod passing longitudinally through said pulley and adapted at one end to engage the said spring at its divided portion, a finger fixed on the other end of said rod, means for maintaining said rod and finger in a normal position, means actuated by a movement of said lever for moving the said finger and rod to spread the parts of said spring, and means controlled by a movement of the said lever in making and breaking the circuit to the motor.

9. The combination with an electric motor and its armature-shaft, of a lever pivoted in said motor-frame and adapted to be actuated 120 by foot-power, a pulley loose on said shaft, a cup-shaped sleeve fixed on said shaft, a divided spring secured on one side of said pulley, a rod passing longitudinally through said pulley and adapted at one end to engage the said spring 125 in its divided portion, a finger on the opposite

end of said rod, a button placed centrally in the side of the pulley opposite the said spring and having a recess therein, a finger fixed in said rod and extending into and through the 5 recess in said button, means for normally maintaining said rod and finger in position, a bearing-ball fixed in the outer end of said button, a wedge-plate carried by said lever and adapted upon the movement of said lever to 10 press the said button and to actuate the said spring through the said rod and finger, and means controlled by a movement of the said lever for making and breaking the electric circuit to the motor.

15 10. In combination with an electric motor and its armature-shaft, of a lever pivoted in said motor-frame and adapted to be actuated by foot-power, a pulley loose on said shaft, a cup-shaped sleeve fixed on said shaft, a divided 20 spring secured on one side of said pulley, a rod passing longitudinally through said pulley and adapted at one end to engage the said spring in its divided portion, a finger on the opposite end of said rod, a button placed centrally in 25 the side of the pulley opposite the said spring and having a recess therein, a finger fixed in said rod and extending into and through the recess in said button, means for normally maintaining said rod and finger in position, a bearing-ball fixed in the outer end of said button, a wedge-plate carried by said lever and adapted 30 upon the movement of said lever to press the said button to actuate the said spring through the said rod and finger, an arm pivoted in said motor-frame, a connection between said arm and said lever, a contact carried at the end of said arm, an electric terminal secured in said frame, a spring for normally maintaining said arm against said connection whereby a movement of the said lever causes the making and breaking of the 35 electric circuit to the motor through said contact and terminal.

11. The combination with an electric motor and its armature-shaft, of a lever pivoted in the motor-frame and adapted to be actuated by foot-power, means for adjustably limiting the movement imparted to said lever, a clutch on said shaft, means controlled by the movement 45 of said lever to make and break the electric circuit to said motor, and means actuated by the movement of said lever for engaging and disengaging said clutch.

12. The combination with an electric motor and its armature-shaft, of a lever pivoted in said motor-frame and adapted to be actuated by foot-power, means for adjustably limiting the movement imparted to said lever, a clutch on said shaft, means in connection with said 55 lever and adapted to normally exert a pressure against the free member of said clutch, means for normally maintaining the lever in position with the aforesaid means performing

its function, means actuated by the movement of said lever to engage and disengage the said clutch, and means controlled by a movement of said lever to make and break the electric circuit to the motor.

13. The combination with an electric motor and its armature-shaft, of a lever pivoted in 70 said motor-frame and adapted to be actuated by foot-power, a screw adjustably mounted to limit the movement imparted to said lever, a bracket integral with said lever, electrical terminals, an arm pivoted at one of said terminals, a contact carried by said arm and adapted to be electrically connected to the other terminal, a block extending between said bracket and said arm, a spring for normally maintaining said bracket and arm in such position that 80 the said contact and terminal are electrically disconnected, a spring for maintaining the said arm in position against the said block, and means actuated by the movement of said lever for connecting and disconnecting the said shaft 85 with the devices driven by the motor.

14. The combination with an electric motor and its armature-shaft, of a lever pivoted in said motor-frame and adapted to be actuated by foot-power, means for adjustably limiting 90 the movement imparted to said lever, a pulley loose on said shaft, a cup-shaped sleeve fixed on said shaft, means in connection with said pulley for frictionally engaging the said cup-shaped sleeve, means actuated by a movement of said lever for actuating the aforesaid means, and means controlled by a movement of the said lever for making and breaking the electric circuit to the motor.

15. The combination with an electric motor 100 and its armature-shaft, of a lever pivoted in the motor-frame and adapted to be actuated by foot-power, means for adjustably limiting the movement imparted to said lever, a pulley loose on said shaft, a cup-shaped sleeve 105 fixed on said shaft, a split spring fixed on said pulley, means actuated by the movement of said lever for spreading the parts of said spring causing the same to engage the said cup-shaped sleeve, and means controlled by a movement of said lever in making and breaking the electric circuit to the motor.

16. The combination with an electric motor and its armature-shaft, of a lever pivoted in said motor-frame and adapted to be actuated 115 by foot-power, a screw adjustably mounted to limit the movement imparted to said lever, a pulley loose on said shaft, a cup-shaped sleeve fixed on said shaft, a divided spring secured on one side of said pulley, a rod passing longitudinally through said pulley and adapted at one end to engage the said spring in its divided portion, a finger on the opposite end of said rod, a button placed centrally in the side of the pulley opposite the said spring and having a recess therein, a finger fixed in said rod 120

and extending into and through the recess in said button, means for normally maintaining said rod and finger in position, a bearing-ball fixed in the outer end of said button, a wedge-plate carried by said lever and adapted upon the movement of said lever to press the said button to actuate the said spring through the said rod and finger, an arm pivoted in said motor-frame, a connection between said arm and said lever, a contact carried at the end of said arm, an electric terminal secured in said frame, 5 a spring for normally maintaining said arm against said connection, whereby a movement of the said lever causes the making and breaking of the electric circuit to the motor through 15 said contact and terminal.

Signed by me this 9th day of May, 1904.
